PRECAST, REINFORCED CONCRETE COLUMN CONSTRUCTION

Ollie L. Besinger, 900 S. Broadway, Park Ridge, Ill.
Filed June 15, 1960, Ser. No. 36,351
1 Claim. (Cl. 59—191)

This invention relates to a new and improved precast concrete column construction, and to the method of making the column.

One object of the present invention is to provide a new and improved precast, reinforced concrete column having metal mesh along or just below the surface thereof, to serve as reinforcement, in addition to metal rods and other members embedded in the column.

A further object is to provide a new and improved method of making a column of the foregoing character, in which the metal mesh is employed as a form to contain the concrete when it is poured in making the column, the use of the metal mesh thus obviating any need for any other forms.

It is another object to provide a new and improved column construction of the foregoing character, in which the metal mesh is secured to members extending between a pair of metal end plates and a plurality of intermediate plates, so that the metal mesh will be able to sustain the weight of the poured concrete.

A further object is to provide such a new and improved column construction in which a metal tube, preferably filled with concrete, is arranged to extend between the metal end plates along the central axis of the column, so as to support and interconnect the end plates and intermediate plates, until the concrete has been poured and has hardened, the metal tube also being effective to reinforce the finished column.

Another object is to provide a new and improved column of the foregoing character, in which a guide tube of reduced diameter is welded or otherwise secured to one end of the central reinforcing tube, and in which the other end of the central reinforcing tube is left open to receive the guide tube on the adjacent column section.

Still another object is to provide a new and improved precast, reinforced concrete column which is easy to make and erect, yet is low in cost.

Further objects and advantages of the present invention will appear from the following description, taken with the accompanying drawings, in which:

FIG. 1 is an elevational view, partly in central longitudinal section, showing a precast, reinforced concrete column to be described as an illustrative embodiment of the present invention.

FIG. 2 is an elevational view, partly in section along a line 2—2 in FIG. 1.

FIG. 3 is an end view of one of the column sections, partly in section along a line 3—3 in FIG. 1.

FIG. 4 is a horizontal section, taken generally along a line 4—4 in FIG. 1.

FIG. 5 is a longitudinal view showing the preliminary assembly of the metal reinforcing members for the column, before the pouring of the concrete.

FIG. 6 is an end view, taken as indicated by the line 6—6 in FIG. 5.

FIG. 7 is an enlarged sectional view through the assembly of FIG. 5, taken generally along a line 7—7 in FIG. 5.

It will be seen that FIGS. 1-4 illustrate a column section 10 adapted to be employed in building construction. The column section itself may be of any desired length, but usually corresponds in length to the height of one story of the building. A number of the column sections 10 are connected together, end to end, in building a multi-story building.

2

It will be seen that the column section 10 is provided with upper and lower end plates 12 and 14 which are made of steel or other suitable metal and are employed to transfer loads between adjacent column sections.

5 The end plates 12 and 14 are connected together by a plurality of metal reinforcing rods 16 which are embedded in a mass of concrete 18. The surface of the concrete 18 is covered with metal mesh 20 which is partly embedded in the concrete 18. A layer of plaster 22 may be applied over the mesh 20 to cover the mesh for fireproofing purposes, and to smooth over the outer surface of the column 10.

It is preferred to provide a large diameter reinforcing tube 24 along the longitudinal axis of the column 10, so 15 as to interconnect the end plates 12. The tube 24 is preferably filled with a mass of concrete 26.

To provide for and facilitate preliminary alignment of the column sections, the opposite ends of each column section 10 are preferably provided with male and female dowels or guide members 28 and 30. In this case, the female guide member 30 is formed by the open lower end portion of the central reinforcing tube 24. It will be seen that the lower end of the tube 24 is welded or otherwise secured into an opening 32 in the lower end plate 14. In this case, a wall or partition 34 is mounted in the 20 reinforcing tube, near its lower end, to prevent the concrete 26 from entering the lower end of the tube 24.

In the illustrated construction, the male guide member 28 takes the form of a guide tube of reduced diameter 30 which is welded or otherwise secured into the upper end of the central reinforcing tube 24. The guide tube 28 extends through an opening 35 in the upper end plate 12. The tube 28 may be welded or otherwise secured to the plate 12. It will be seen that the upper end portion of 35 the guide tube 28 extends above the plate 12 and is adapted to be received in the open guide portion 30 of the overlying column section.

In the illustrated arrangement, the central reinforcing tube 24 extends through openings 38 in a plurality of 40 intermediate plates 40 which are somewhat smaller than the end plates 12 and 14. The intermediate plates 40 may be welded or otherwise secured to the central reinforcing tube 24.

In making the column 10, the end plates 12 and 14, the reinforcing rods 16, the central reinforcing tube 24, the guide tube 28, and the intermediate plates 40 are 45 preferably assembled and welded together, as shown in FIG. 5. The reinforcing rods 16 may be mounted in holes 42 formed in the end plates 12 and 14. The concrete 26 within the central reinforcing tube 24 is preferably cast and allowed to set before the central reinforcing tube is assembled with the other reinforcing members.

It will be apparent that the assembly of reinforcing members shown in FIG. 5 forms a rigid structure. The 55 reinforcing rods 16 may extend through openings 44 in the intermediate plates 40. The metal mesh 20 is secured to the reinforcing structure of FIG. 5 to contain the concrete 18 when it is cast around the rods 16 and the tube 24. The metal mesh 20 may be made of expanded 60 sheet metal or of wire. Preferably, the metal mesh 20 is supported by angle members 48 which extend between the end plates 12 and 14 and are secured to the corners of the intermediate plates 40. The metal mesh 20 may be welded or otherwise secured to the angle members 48 and to 65 the end plates 12 and 14 and the intermediate plates 40. Initially, only three sides of the metal mesh 20 are secured to the angle members 48, these sides being designated 20a, 20b and 20c in FIG. 7. The column is placed in a horizontal position so that the metal mesh 70 forms a three-sided trough, into which the wet concrete is poured to embed the reinforcing rods 16 and the central reinforcing tube 24. Thus, the three sides of the metal

mesh 20a, 20b and 20c provide a form which is filled with wet concrete. The metal mesh contains the concrete, except for a small amount which oozes through the mesh and partially embeds the mesh when the concrete has hardened. Thus, the metal mesh obviates any need for a special form to hold the concrete. After the three metal mesh sides 20a, 20b and 20c have been filled with concrete, a fourth metal mesh side 20d may be added, if desired, so that all sides of the column will be the same. Alternatively, the metal mesh may be omitted from the fourth side of the column.

After the main mass of concrete 18 has hardened and cured sufficiently, the column section may be erected, as shown in FIGS. 1 and 2. Anchor bolts 50 may be employed to secure the lower end plate 14 to a concrete footing or other foundation 52. As shown, the bolts 50 extend through holes 53 in the lower end plate 14. A leveling plate 54 may be provided between the lower mounting plate 14 and the footing 52. If necessary, cement grout may be employed between the leveling plate 54 and the footing 52 to provide a firm bearing between the leveling plate and the footing. After the column 10 has been erected, a concrete floor 56 may be poured over the footing 52 so as to embed the lower mounting plate 14 and the bolts 50.

As already indicated, two or more of the column sections 10 may be stacked end to end. The adjacent upper and lower end plates 12 and 14 are welded or otherwise secured together to transmit loads between the column sections. In erecting the column sections 10, the female guide member 30 at the lower end of the upper section is slipped over the male guide member 28 which projects above the lower column section. These guide members facilitate the preliminary alignment of the column sections. However, a substantial clearance is provided between the guide members 28 and 30 so that the upper column section may be moved relative to the lower section until the upper section is precisely aligned with the lower section and is exactly plumb. In some cases it may be necessary to insert thin shims, made of sheet metal or the like, between the plates 12 and 14, so that the upper column section will be plumb. Once the upper column section has been accurately positioned, the plates 12 and 14 may be welded together.

It will be seen that the plates 12 and 14 are larger than the rest of the column 10 so as to form a ledge upon which girders or beams 60 may be supported. In this case, metal reinforcing and anchoring members 62 are embedded in the girders 60 and are welded to the end plate 14. As shown, joists 64 may be strung between the girders 60. Both the girders 60 and the joists 64 are preferably made of precast, reinforced concrete. The joists 64 may be secured to the girders by means of metal anchors 66 and 68 which are embedded in the joists and the girders and are welded together.

After the column sections 10 have been erected, the layer of plaster 22 may be applied to the outside of the column sections, so as to cover the metal mesh 20 and the corner supporting members 48. The metal end plates 12 and 14 may also be covered with plaster or embedded in concrete with the use of simple forms. Thus, the entire outer surface of the column will be covered with fireproof material. The metal mesh 20 forms an excellent base for the plaster, because the plaster adheres securely to the metal mesh and to the hardened concrete 65 which projects through the openings in the mesh. The plaster on the outside of the column gives the column a smooth surface and a finished appearance.

The columns of the present invention are precast and cured before they are erected, so that they are capable of supporting their full normal loads as soon as they are erected. This factor greatly expedites the construction of the building, because there is no need to wait for concrete to cure as the building is erected. The column sections are connected together with a high degree of rigidity by the welded joints between the end plates of the column sections. Thus, buildings made with the column sections of the present invention are particularly resistant to earthquakes.

The use of forms is obviated during the casting of the columns of the present invention. This greatly facilitates and expedites the casting of the columns, so that the cost of the columns is minimized.

Various modifications, alternative constructions and equivalents may be employed without departing from the true spirit and scope of the invention, as exemplified in the foregoing description and defined in the following 20 claim.

I claim:

A precast, reinforced concrete column, comprising a pair of metal end plates, a central tubular member extending between said end plates and rigidly secured thereto, said tubular member having an open portion at one end forming a female guide member and a reduced portion at the other end extending beyond one of said end plates and forming a male guide member, a plurality of intermediate plates strung on said tubular member at intervals between said end plates, a plurality of reinforcing rods disposed around said tubular member and extending between said end plates, said rods being rigidly secured to said end plates, a mass of concrete disposed between said end plates and embedding said tubular member and said reinforcing rods, and a tube of metal mesh disposed around said concrete and partly embedded therein, said tube of metal mesh being secured to said end plates and to said intermediate plates and having supporting members extending therealong, said end plates and said intermediate plates maintaining the shape of said tube, said end plates being larger than the cross section of said tube and having edge portions projecting outwardly therefrom, said end plates being effective to transfer stresses to said rods and said central tubular member.
